UNITED STATES PATENT OFFICE.

WILLIAM ALEXANDER SKEEN CALDER AND WILLIAM HAROLD PALMER, OF BIRMINGHAM, ENGLAND, ASSIGNEES TO CHANCE AND HUNT, LIMITED, OF BIRMINGHAM, ENGLAND.

PROCESS FOR CONDENSING THE ACID FUMES EVOLVED DURING THE CONCENTRATION OF SULPHURIC ACID.

Application filed December 13, 1922. Serial No. 606,697.

To all whom it may concern:

Be it known that we, WILLIAM ALEXANDER SKEEN CALDER, a subject of the King of Great Britain, and residing at Ravens-
5 thorpe, Harborne, Birmingham, England, and WILLIAM HAROLD PALMER, a subject of the King of Great Britain, residing at 208 Londonderry Lane, Smethwick, Birmingham, England, have invented a new and
10 useful Improved Process for Condensing the Acid Fumes Evolved During the Concentration of Sulphuric Acid, of which the following is a specification.

Various difficulties are met with when
15 condensing the acid fumes evolved during the concentration of sulphuric acid when the means employed consist in passing the gases carrying the fumes through a main or pipe or the like, having in it a constric-
20 tion.

In the invention described in the British specification No. 126,320, of which one of us was a part-inventor, a process was described which consisted in causing gases containing
25 such fumes to pass through a constriction in a main pipe or the like, while at a tem-
perature above 95° and below 135° C. at a minimum speed of 20 feet per second.

With a minimum speed of 20 feet per sec-
30 ond obstructing means must be provided in the restricted zone for causing the gases to change their direction, otherwise the mini-
mum speed of the gases should be 40 feet per second.

35 Good results are obtainable by this process and it is quite possible with a suitable velocity of the gases for the constricted por-
tion of the pipe to be no more than eight inches long.

40 This invention relates to an improvement in this process.

We have now discovered that better and more regular results are obtained when the water content of the gases under treatment
45 is between 20 and 35% by volume of water vapour.

The water is conveniently introduced in the form of steam or as a fine spray, or the gases may be caused to pass through water
50 or through a tower or box packed with inert material over which water is caused to flow.

The accompanying drawings illustrate our invention.

Figure 1 is a cross section of a condensing arrangement, and Figure 2 a sectional elevation, while Figures 3 and 4 are similar views of a modification.

Referring to Figures 1 and 2, *a* is a main through which the gases to be treated flow, while *b* is a steam pipe by which the gases are given the content of water in accordance with this invention.

c is a constriction in main *a* and *d* are tubes therein formed of glass or other suitable acid resisting material.

The cross section of constriction *c* and that of the tubes *d* and their length, vary according to circumstances but must be such that at the working speed of the fan employed, the velocity of the gases in the
70 tubes *d* will be at least 40 feet per second.

In this construction the constricted zone is formed in two ways, viz. by the relatively small size of the portion *c* with respect to the main *a* and by tubes *d* in the main. The tubes *d*, however, if of sufficient length and sufficiently small (but not so small as to become blocked with acid) may alone constitute the constriction.

Referring to Figures 3 and 4, *a* is a main, *b* a pipe for leading steam into main *a*, and *c* are sets of bars formed of glass or other acid resisting material, one set of bars being staggered with regard to the adjacent set or sets of bars. *e* is a vessel into which the
85 condensed acid passes.

The number of sets of bars must be such that at the working speed of the fan em-
ployed the velocity of the gases becomes at
90 least 20 feet per second.

What we claim is:—

1. A process for condensing acid fumes evolved during the concentration of sulphuric acid, which consists in adding water to the gases conveying the acid fumes in such amount that the water content of such gases is after the addition of water between 20 and 35% by volume of water vapour, then causing such gases while at a temperature above 95° C. and below 135° C. to travel
95 while in a constricted portion of a container at a speed adapted to condense the fumes.

2. A process for condensing acid fumes evolved during the concentration of sulphuric acid, which consists in injecting steam into the gases conveying the acid
100

fumes in such amount that the water content of such gases is after the addition of water between 20 and 35% by volume of water vapour, then causing such gases while at a temperature above 95° C. and below 135° C. to travel while in a constricted portion of a container at a speed adapted to condense the fumes.

3. A process for condensing acid fumes evolved during the concentration of sulphuric acid, which consists in adding water to the gases conveying the acid fumes in

such amount that the water content of such gases is after the addition of water between 20 and 35% by volume of water vapour, 15 then causing such gases while at a suitable temperature above 95° C. to travel while in a constricted portion of a container at a speed adapted to condense the fumes.

In testimony that we claim the foregoing 20 as our invention we have signed our names this 1st day of December, 1922.

WILLIAM ALEXANDER SKEEN CALDER.

WILLIAM HAROLD PALMER.
